No. 627,949.

Patented June 27, 1899.

W. J. WORDEN.
APPAREL APPURTEANCE.

(Application filed June 9, 1898.)

(No Model.)

UNITED STATES PATENT OFFICE.

WILL J. WORDEN, OF CHICAGO, ILLINOIS, ASSIGNOR OF ONE-HALF TO
THOMAS J. PRINGLE, OF MILWAUKEE, WISCONSIN.

APPAREL APPURTEMENTE.

SPECIFICATION forming part of Letters Patent No. 627,949, dated June 27, 1899.

Application filed June 9, 1898. Serial No. 683,025. (No model.)

To all whom it may concern:

Be it known that I, WILL J. WORDEN, a citizen of the United States, residing at Chicago, in the county of Cook and State of Illinois, 5 have invented new and useful Improvements in Apparel Appurtenances, of which the following is a specification.

My invention contemplates the provision of a device for connecting the waist and skirt 10 of a dress together and securing a belt or the like in position, and its novelty and many advantages will be fully understood from the following description and claims when taken in conjunction with the annexed drawings, 15 in which—

Figure 1 is a sectional view illustrating my improved device in operation. Fig. 2 is a rear elevation of the same. Fig. 3 comprises perspective views of the two members of the 20 device. Fig. 4 is a rear elevation of a modification.

Referring by letter to the said drawings, and more particularly to Figs. 1 to 3 thereof, A is the waist of a dress, having a buttonhole at a. 25 B is the skirt, the lapped portions of which have coincident buttonholes b.

C is a belt of leather or other suitable material, and D is my improved device for connecting the waist and skirt together and securing the belt in position. The said device 30 D is made of German silver or other material suitable to the purpose, and comprises a member E and a member F, which for the sake of convenience I will hereinafter term a "button" and a "retaining-plate," respectively.

The button E has a flat head c at one end, which is designed to rest at the inner side of the waist A, and a shank or stem d, which is flat, as shown, and is designed to be passed 35 through the coincident buttonholes a b of the waist and skirt after the manner shown in Fig. 1, when by reason of its being flat it will be securely held against turning. At its outer end the shank or stem d is reduced, as indicated by e, and provided with the elongated head f, so as to permit of it being placed in engagement with the retaining-plate F. The said retaining-plate, which is designed to rest 40 at the outside of the skirt, is provided with an elongated aperture g of a size for the pas-

sage of the head f, and is also provided with a marginal flange h along one edge and a skirt i on the same, as shown.

In using my improved device the shank or stem of the button is passed through the apertures a b of the waist and skirt, as before described, and the plate F is held in a position at right angles to that shown in Fig. 1 and is placed on the shank and given a quarter-turn, so as to enable the head f to secure it in position. With this done it will be seen that the plate retains the button in position and is securely held in turn by the button. After the button and retaining-plate are placed and secured in position, as described, 55 the belt C is secured about the waist and is arranged so as to rest below the flange h of the waist and within the depending skirt i thereof. By reason of this the belt is held against moving upwardly, and at the same 60 time the plate F is prevented from turning and becoming disengaged from the button. The button is also prevented from turning by reason of its flat shank resting snugly in the coincident buttonholes of the waist and 65 shank, and it will therefore be appreciated that there is no liability of any part of the device casually working loose.

It will be apparent from the foregoing that my improved device is adapted to be easily 80 and quickly placed in position and as readily removed when desired; also, that it securely holds the waist, skirt, and belt in their proper relative positions and does not in any way detract from the appearance of the dress. 85

In Fig. 4 is illustrated a modification of the invention which is designed for use when a girdle C' and a ribbon C² are to be worn about the waist in lieu of a belt such as shown in Figs. 1 and 2. The button E of this modified 90 device is similar in all respects to that shown in Figs. 1 to 3 and is similarly used. The retaining-plate F' is also similar to the plate F, before described, with the exception that it is provided with slots h' instead of a flange h. 95

In using the improved device the plate F', with the girdle extending through the slots thereof, is connected to the button E in the manner before described after the shank of the button is passed through the coincident 100

buttonholes of the waist A and skirt B. The girdle C' is then tied about the waist, after which the ribbon C² is placed over the girdle and the plate F' and is suitably secured in position.

In both embodiments of my invention it will be noticed that the retaining-plate and the belt are placed in engagement, and in consequence each serves to effectually prevent casual movement of the other.

Having thus described my invention, what I claim is—

1. The combination of a waist and a skirt having coincident apertures or buttonholes, a button having a flat shank resting snugly in the apertures or buttonholes of the waist and skirt and provided at its outer end with the reduced portion e and elongated head f, a retaining-plate having the elongated aperture for the passage of the head f of the button, and a suitable belt secured about the waist and engaging the retaining-plate, substantially as and for the purpose set forth.
2. The device described comprising the button having the flat shank with the flat head c at one end and the reduced portion e and elongated head f at its opposite end, and a retaining-plate having an elongated aperture for the passage of the head f of the button and also having belt-holding means, substantially as specified.

3. The device described comprising the button having the flat shank with the flat head c at one end and the reduced portion e and elongated head f at its opposite end, and a retaining-plate having an elongated aperture for the passage of the head f of the button, and also having the belt-engaging flange h at its upper edge and the skirt i depending therefrom, substantially as specified.

In testimony whereof I have hereunto set my hand in presence of two subscribing witnesses.

WILL J. WORDEN.
